UNITED STATES PATENT OFFICE.

IZUMI SHIKUSAWA, OF CHIGUSA MACHI, JAPAN.

PROCESS OF SETTING TACKS IN PORCELAIN TEETH.

1,427,237.

Specification of Letters Patent. Patented Aug. 29, 1922.

Application filed July 27, 1918. Serial No. 247,079.

To all whom it may concern:

Be it known that I, IZUMI SHIKUSAWA, a subject of the Emperor of Japan, and resident of 36 Ikenouchi, Chigusa Machi, 5 Aichi Gun, Aichi Ken, the Empire of Japan, have invented new and useful Improvements in Processes of Setting Tacks in Porcelain Teeth, of which the following is a specification.

10 The invention relates to a process of anchoring or setting tacks in artificial teeth. The primary object of the invention is to simplify the anchoring or setting of tacks in an artificial tooth, so as to permit the 15 proper support thereof and the firm and secure fastening of the tack in position, the tooth being formed with a hole having a medial enlarged portion, and this hole is made by a core placed within a mold used 20 for the formation of the artificial tooth, the core being made from inflammable substance so that when the artificial tooth is heated for the finishing of the same after the formation thereof, such heat will burn up the 25 core, and thus free the hole therefrom for the reception of a tack or tacks to be subsequently set or anchored therein after the removal of the formed tooth from the mold.

Another object of the invention is to 30 firmly and securely fix a metallic tack, or the like, within an artificial tooth without requiring skilled labor and also eliminate the following out of the steps of processes heretofore known for a like purpose, which 35 are expensive and oftentimes unsatisfactory in results.

A further object of the invention is to 40 provide a process, wherein headed tacks can be employed as a fastening medium for the artificial tooth, and can be readily and conveniently anchored within the body of said tooth, the cavity or hole for the tack being formed in a novel manner when the tooth is molded for subsequent reception of the 45 headed tack, which is also fastened within the hole or cavity in a novel manner.

Other objects and advantages will be derived from the use of the process, which will appear from the following detailed description, taken in connection with the accompanying drawings, illustrating the preferred embodiment of the invention, showing by way of example the molds required for practicing the invention and an artificial tooth made thereby, it being understood that 55 changes, variations and modifications may

be resorted to in the invention, such as come properly within the scope of the appended claims.

In the accompanying drawing:

Figure 1 is a plan view of one section of the mold for forming the artificial teeth and looking toward the inner-face thereof.

Figure 2 is a view similar to Figure 1 of the other section of the mold looking toward its inner-face, showing in detail plural artificial teeth in the cavities therein.

Figure 3 is a vertical transverse sectional view of the section shown in Figure 1.

Figure 4 is a view similar to Figure 3 taken through the section shown in Figure 2 with the artificial tooth removed from its cavity.

Figure 5 is a vertical transverse sectional view through the mold when assembled with an artificial tooth therein and the core in place.

Figure 6 is a side elevation of the core removed.

Figure 7 is a face view thereof.

Figure 8 is a side elevation of several headed tacks.

Figure 9 is an elevation of an artificial tooth looking toward the inner-side thereof.

Figure 10 is a view similar to Figure 9 showing the tacks anchored therein.

Figure 11 is a transverse sectional view taken on the line A—B of Figure 10.

Figure 12 is a vertical sectional view taken on the line C—D of Figure 10.

Similar reference characters indicate corresponding parts throughout the several views in the drawing.

To exemplify the carrying of the process into practice with reference to the accompanying drawing there is employed a pair of mold sections 1 and 2, respectively, each being in the form of a substantially rectangular shaped body having formed in the inner-face thereof a plurality of cavities or recesses of the desired shape conforming to the required teeth, the sections being adapted for close contacting relation on the bringing of the sections together with their inner-faces adjoining each other. The cavities or recesses in the inner-face of one section will coincide or register with the cavities or recesses corresponding thereto in the inner-face of the adjoining section, the section 1 being formed with notches 3 in its marginal edge, while the section 2 is formed with protuberances 4 correspondingly to the

notches 3 for engagement therein, and in this manner the said sections when joined will be properly matched and interlocked with each other. Prior to the joining of the 5 sections 1 and 2 the said section 1 has introduced into its cavities therein kneaded potters-clay, which is the material from which artificial teeth are made, whereupon the section 2 is placed upon the section 1 10 for the interlocking of these sections together to permit the formation of the artificial teeth.

The section 2 in each cavity therein has further formed in its body a pocket 5, which 15 is in the form of an elongated slot with a medial enlarged portion 6, and into this pocket is placed a correspondingly shaped core 7, made from inflammable substance, such as a briquet, shaped as is clearly illustrated in Figures 6 and 7 of the drawing. The core 7 when held in the pocket 5 in the molded section 2 will project into the space formed by the cavities in the respective mold sections when joined together for the 20 shaping of the artificial teeth, so that a recess will be made in the artificial tooth at the inner-side thereof on the subsequent finishing of the artificial tooth in the baking thereof.

30 In the making of artificial teeth the mold sections 1 and 2 are initially separated from each other and a core 7 is placed within each pocket 5 in the respective cavities in the mold section 2, whereupon the cavities in the 35 mold section 1 are filled with kneaded potters-clay, which is the material employed for making the artificial teeth, and thereafter said mold section 2 is superimposed upon the mold section 1 for the joining of 40 these mold sections in the manner as shown in Figure 5 of the drawing and pressure is exerted upon said mold sections thus joined for compressing the material into the cavities in the respective mold sections for 45 the proper formation of the artificial teeth thereby. The joined mold sections are permitted to stand for the drying of the material in the cavities, and when said material is fully coagulated the mold sections are 50 moved from the dried artificial teeth formed thereby, which have therein the core 7, and thereafter the formed teeth are baked for the finishing thereof, the baking being effected by the heating of the teeth. During 55 the heating period each core 7 is burned up so that the finished tooth will have present therein a hole or indenture 9 correspondingly shaped to the burned core 7.

Next, there is inserted a headed tack 8 in 60 the hole 9 formed by the burned core in the body of the tooth, the head of the tack being inserted in the enlarged central portion 10 of the hole 9 and is moved laterally toward

either end of said hole for the anchoring of the headed tack in the tooth, as the walls 65 of the recess will engage the head of the tack and hold it fast in such a manner that the tack cannot work loose or become freed from the tooth unless excessive pressure is applied to the tack to remove it in the 70 direction of the enlarged portion 10 of the hole 9 for the return of said tack to its initial or former position, that is, at the center of the hole, which would permit the 75 free removal of the tack from the tooth. It is preferable to anchor several tacks in the tooth, and in this event the medial portion of the recess after the anchoring of the tacks is filled with potters-clay as at 11 in Figures 10 and 11, this material being baked thus 80 closes the recess to prevent the removal of the tacks from the tooth and at the same time closes the hole in the inner-face of the tooth.

It will be apparent that the tacks when 85 anchored in the teeth cannot work loose or fall from the same.

From the foregoing it is thought that the manner of use of the mold and the carrying of the process into practice will be clearly 90 understood, and, therefore, more extended explanation has been omitted.

What is claimed is:

1. The process of making an artificial tooth provided with anchoring tacks projecting 95 from its rear face, which consist in first molding the body of the tooth in a double mold with an inclosed core of material destroyable by the heat used in baking the tooth, to leave a transverse elongated slot in 100 the back of the tooth having an intermediately located enlargement, a plurality of headed tacks in the slot introduced through the enlargement, and locating the headed ends of the tacks at opposite ends of 105 the slot, and then anchoring the tacks in the tooth by material susceptible to solidification.

2. The process of making artificial teeth provided with anchoring tacks projecting 110 from its rear face, which consist in first molding the body of the tooth in a divisible mold with an embedded core of material destroyable by the heat used in the baking of the tooth, to leave a transverse elongated 115 slot in the back of the tooth with an intermediately located enlargement, then introducing a plurality of headed tacks in the slot through the enlargement and locating the headed ends of the tacks at opposite ends 120 of the slot, and then anchoring the tacks in the tooth at opposite ends of the slot by material susceptible to solidification.

In testimony whereof I affix my signature hereto.

SHIKUSAWA, IZUMI. [L.S.]
